UNITED STATES PATENT OFFICE.

GEORGE W. CHRISTIANS, OF NEW YORK, N. Y.

ELECTRIC FUSE.

1,028,328.

Specification of Letters Patent.

Patented June 4, 1912.

Application filed December 27, 1911. Serial No. 668,067.

To all whom it may concern:

Be it known that I, GEORGE W. CHRISTIANS, a citizen of the United States, residing at New York, in the county of New York and State of New York, have invented a certain new and useful Improvement in Electric Fuses, of which the following is a specification.

The invention relates to electric fuses, and 10 consists in the construction, hereinafter set forth, whereby a long fuse strip adapted for high potential currents may be conveniently supported and protected. The device comprises a central rod of insulating and preferably refractory material, on the ends of which are metal caps, provided with hooks on their edges, which hooks serve as points of attachment for a continuous fuse wire, which extends between said caps and lengthwise of said rod. A suitable covering of refractory insulating material envelops the fuse strip and rod.

In the accompanying drawings—Figure 1 is an exterior view of the complete device. 25 Fig. 2 shows the same, with the covering of insulating material removed. Fig. 3 is a longitudinal section, and Fig. 4 shows one of the metallic end caps separately and in perspective.

30 Similar letters of reference indicate like parts.

The fuse strip holder A is preferably of porcelain, or other refractory insulating material, and is in the form of a rod with an 35 enlargement B at each end. To said enlargements are applied the metal caps C. The edge of each cap, as shown in Fig. 4, is cut to form arms D which, after the cap is applied to the holder end, are bent twice at 40 right angles to fit under the shoulder of the enlargement and then turned back at their extremities to form hooks E. After the caps are in place, the fuse wire or strip F is secured at its end to one hook and then carried to and fro lengthwise of the holder so 45 as to engage with all of the hooks successively, and the free end is finally fastened at the place of beginning.

In order to protect the fuse wire F and also to guard adjacent objects from the effects of blowing the same, a suitable covering is desirable. A preferable form of such cover, here illustrated, is composed of a filling G of plaster, or other comminuted refractory material, and an outer envelop H 50 of non-combustible fabric, such as asbestos cloth. I may apply this covering by first laying the cloth flat, spreading thereon a layer of plaster mixed with water, and then a layer of dry plaster, and, finally, tightly 55 wrapping the coated and plaster-covered cloth around the fuse strip and holder, so that the plaster is caused to fill the space around the strip and between the same and holder. The cover may be secured in place 60 by a cord wound around it, as shown at I, Fig. 1. As soon as the plaster hardens, the device is ready for use in the ordinary way.

I claim:

1. An electric fuse, comprising a rod of 70 insulating material, terminals of conducting material thereon, and a continuous fuse wire longer than said rod, extending parallel thereto and having loops engaging with said terminals at a plurality of points.

2. An electric fuse, comprising a rod of 75 insulating material, end caps of conducting material thereon, having integrally formed hooks on their circumferential edges, and a plurality of fuse strips connected to said 80 hooks and extending lengthwise of said rod.

3. An electric fuse, comprising a rod of insulating material, having enlargements at its ends, caps of conducting material on said enlargements, a fuse strip connected at a 85 plurality of points to said caps and extending lengthwise of said rod, and an insulating covering disposed between said enlargements and inclosing said fuse strip and rod.

In testimony whereof I have affixed my 90 signature in presence of two witnesses.

GEORGE W. CHRISTIANS.
